COMPOSITE PLASTER BASE AND INSULATING UNIT

Cecil R. Pemberton, Silver Spring, Md.

Application June 15, 1938, Serial No. 213,919

11 Claims. (Cl. 20—4)

The present invention relates to a composite plaster base and insulating unit for building construction.

It is an object of the invention to provide a composite plaster base and insulating unit embodying a rigid plaster supporting base and insulating material permanently attached to the base so that the same may be applied directly to studding or other spaced supporting members, such as furring strips, roof rafters etc. in a single operation, thereby eliminating the separate handling and installation of insulating material and lathing in the building operation.

Another object is to provide a composite plaster base and insulating unit in which a rigid base member of novel construction is provided on one side with a plaster receiving surface and on the other side with insulating elements which are supported solely by the base in such a manner as to be wholly disposed between adjacent studding or other supporting elements when the unit is installed.

Another object of the invention is to provide a composite plaster base and insulating unit in which the insulating material is effectively supported over its entire surface area so that it is prevented from packing down after installation in vertical walls and is also protected against moisture.

For a better understanding of the invention, reference is made to the accompanying drawings which illustrate preferred embodiments thereof and in which,

Fig. 1 is a sectional perspective view of the front face of a portion of a building wall embodying the invention,

Fig. 2 is a sectional perspective view of the back of the unit shown in Fig. 1,

Fig. 3 is a front elevation of a wall embodying the invention, with parts broken away,

Fig. 4 is a sectional view on the line 4—4 of Fig. 3,

Fig. 5 is a sectional view on the line 5—5 of Fig. 3,

Fig. 6 is a sectional view on the line 6—6 of Fig. 5,

Fig. 7 is a sectional perspective view of a portion of a wall embodying a modified form of the invention, and

Fig. 8 is a sectional perspective view of a portion of a wall embodying a further modification.

The form of the invention illustrated in Figs. 1 to 6 inclusive will be described first. The supporting members 10 which will be referred to as studs for convenience may be furring strips, raft-

ers, studding elements, floor joists, or the like, commonly employed in building construction and to which floors, walls and ceilings are applied. These supporting elements are normally placed on standard centers of 12", 16" or more and the units embodying the invention will be made in sizes and the elements thereof dimensioned for application to supports placed on all standard centers.

The base sheet or panel 11 forming a part of 10 the invention is substantially the same in all forms.

The base panel 11 may be of different lengths depending on the spacing between the studding members but in each size classification is preferably long enough to span the intervening spaces between at least three studs. The unit of Fig. 1 is shown as spanning the spaces between four studs, the ends terminating on the center of the studs at each end of the unit. 20

The base panel consists of a plurality of lath members 12 maintained in spaced parallel relation and extending lengthwise of the panel and coextensive therewith. The lath members, which may be ordinary wood lath or composition strips 25 formed of cement plaster and asbestos, are secured between a facing sheet 13 and a backing sheet 14 of fibrous material such as paper felt. Each of these sheets is provided on its inside face with a coating 15 of asphalt or similar sealing and adhesive material which serves to secure the laths and sheets together as a unit and also seals the panel against the passage of air or moisture therethrough. In making the unit, the asphalt is applied hot to one surface of each 30 sheet and the lath is placed in position on the coated surface of one sheet and the other sheet is then applied with its coated surface against the lathing strips, thereby forming an integral unit. 40

The facing sheet 13 is provided with a plurality of small openings 16 uniformly spaced over the area of the panel. These openings coincide with the spaces 17 between the lathing strips and allow the entry of a part of the plaster 19 applied 45 to the face so as to form interlocking plaster keys 18. It will be noted from an inspection of Figs. 4, 5 and 6 that the plaster keys will fill the cross sectional area of the spaces 17 between the laths, thereby forming sealing stops which divide 50 the spaces 17 into a plurality of dead air cells, thus contributing to the insulating efficiency of the unit.

A plurality of pads or batts 20 of insulating wool material, which may be any commercial 55

fibrous or wool-like material, such as Balsam wool or the like, are adhesively secured to the outer face of the backing sheet 14 in spaced relation, each pad covering the area of the panel which 5 will lie between studs when the unit is in position so that the rear face of the panel is left clear along the lines of contact with the studding.

By mounting the insulating pads on the panel in spaced relation as described, it will be observed that the plane rear face of the panel makes 10 direct contact with the studs so that the front faces of the panels will be flush with each other. This is considered important because if the panels were nailed to the studding with intervening layers of insulating material, the resulting wall surface would be uneven due to the variation in the compression of the intervening insulation in nailing the units in place.

The insulating pads or batts are secured to 20 the rear face of the panels 11 by means of a layer of hot asphalt 21 applied to the backing sheet 14 before the insulation is applied thereto. In order to protect, and additionally support the insulation and increase the water resistant properties 25 of the entire unit, each pad or batt of insulating material is enclosed by a wrapping of water-proofed crepe paper 22. The crepe paper is adhesively secured to the batt by means of hot asphalt and the sides are turned inwardly around 30 and under the edge of the batts as indicated at 23 and secured directly to the panel 11 by means of the asphalt layer 21. The ends of the paper covering are also turned inwardly and similarly secured as seen at 24.

35 The insulating batts are thus seen to be entirely enclosed in a water proof covering and are supported on all sides so that there is no possibility of the insulation packing down after installation.

40 In order to increase the rigidity of the units and to prevent bending or rolling of the same in handling before installation, a plurality of laths or strips 25 are cemented to the rear face of the panel 11 at right angles to the laths 12. 45 These strips are preferably disposed centrally of the area covered by the insulation pads 20. While the hot asphalt used in securing the pads to the backing sheet forms an efficient means of attaching the reinforcing strips in position, they 50 may be additionally secured to the laths 12 by suitable metallic clips or nails, if desired.

The ends of the composite panels 11 are finished by applying an adhesive binding tape 26 over the edges. This tape serves to seal the ends 55 of the spaces 17 between the laths and also adds to the finished appearance of the unit as a whole.

In applying the units in the fabrication of a wall, the complete unit is placed in position in one operation with the individual envelopes or 60 pads of insulation sliding into position in the spaces between adjacent studs and the exposed areas of the backing sheet 15 of the panel 11 directly engaging the faces of the studding. The units are then secured in position by nails 27 65 driven through the panels into the studding.

65 It will be noted that the clear space on the back of the panels between the ends and the adjacent pads is equal to half the thickness of a stud so that the units can be mounted with their 70 ends in abutting relation and centered on the studs.

In the modified form of the invention shown in Fig. 7, the panel 11 is of the same construction as described above. In this embodiment, the 75 crepe paper wrapping or envelope 30 completely

encloses the insulating pad 31, extending around to the back of the pad and having its edges lapped over and sealed as at 32. The ends of the crepe paper wrapping are likewise turned inwardly to seal the upper and lower ends of the insulating pad as at 33. Before the insulating material is enclosed in the paper wrapping, the latter is coated with hot asphalt or the like so as to water proof the same and so that the insulation will be secured to the wrapping on all surfaces.

A plurality of the complete envelopes are secured to the rear face of the panel 11 by means of a hot asphalt layer 34, leaving a space between adjacent envelopes sufficient to receive the studding or other spaced supporting members upon which the unit is to be mounted.

A reinforcing transversely extending lath or strip 35 is mounted on the rear face of the panel centrally of each of the envelopes of insulating material as in the previous case.

If desired, the reinforcing lath or strip may be disposed within the envelope itself and suitable openings provided along the length of the lap seam 32 to expose the strip 35 at intervals. In this way, the strip would be directly cemented to the panel at spaced intervals and would aid in securing the envelope to the panel as well as serving to strengthen the unit against bending or rolling.

In the form of the invention shown in Fig. 8, the insulation which is fitted between the studdings is omitted. This unit may be used where less insulation is required and where an efficient plaster base is the primary objective. This unit also is similar to the panel 11, consisting of backing and facing sheets 36 and interposed spaced parallel laths 38, the whole being secured together by asphalt layers 39 applied to the inner faces of the sheets 36 and 37. A reinforcing strip 40 applied to the rear face of the backing sheet 36 may be provided or in some cases may be omitted if desired. The facing sheet is provided with openings 41 opening into the spaces between the laths 38 to form plaster interlocking keys as described above.

It will be seen from the above that the invention provides a very strong durable and rigid plaster base or wall surfacing member having insulating properties, and also insulation in the form of the pads carried on the back of the panels which pads will engage adjacent studs along the sides and will engage the ends of the pads of adjacent units when a plurality of units are mounted together in making up a wall so that a continuous blanket of insulation will be provided.

While preferred embodiments of the invention have been illustrated and described by way of example, it will be understood that various other modifications and changes in the details may be resorted to without departing from the spirit of the invention as defined in the claims.

I claim:

1. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, and a plurality of individual insulat-

ing pad members adhesively secured to one face of said unit in spaced relation, said insulating pad members being substantially equal in width to the space between the supporting elements to which the unit is to be applied and spaced apart a distance substantially equal to the width of said elements.

2. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, said facing sheet having a plurality of openings therein coinciding with the spaces between said lath members, for admitting plaster applied to said facing sheet into the interspaces between said laths to form interlocking keys and divide said interspaces into separate closed air cells.

3. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, said facing sheet having a plurality of openings therein coinciding with the spaces between said lath members, for admitting plaster applied to said facing sheet into the interspaces between said laths to form interlocking keys and divide said interspaces into separate closed air cells, and a plurality of individual insulating pad members adhesively secured to one face of said unit in spaced relation, said insulating pad members being substantially equal in width to the distance between the supporting elements to which the unit is to be applied and spaced apart a distance substantially equal to the width of said elements.

4. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, and a plurality of individual insulating pad members adhesively secured to one face of said unit in spaced relation, said insulating pad members being substantially equal in width to the distance between the supporting elements to which the unit is to be applied and spaced apart a distance substantially equal to the width of said elements, and a lathing strip secured to the backing sheet inside of said insulating pad members and extending cross-wise of the lathing members between said sheets.

5. A composite plaster base and heat insulating material adapted for direct application to wall studding members or the like as a unit which

comprises, a rigid panel member comprising a facing of fibrous material and a backing sheet of fibrous material in spaced relation thereto, a plurality of wooden laths disposed in parallel spaced relation between said sheets, a coating of asphalt applied to the inner surface of each of said sheets serving to waterproof the same and to secure the sheets and laths together as unit, the facing sheet having a plurality of openings therein coinciding with the spaces between said laths for the entrance of plaster applied to said face to form interlocking keys, pads of insulating material adhesively secured to said backing sheet and spaced apart a distance equal to the thickness of a studding element, whereby said pads will extend between studding members and said backing sheet will directly engage the studding elements when the unit is applied thereto.

6. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, said facing sheet having a plurality of openings therein coinciding with the spaces between said lath members for admitting plaster applied to said facing sheet into the interspaces between said laths to form interlocking keys and divide said interspaces into separate closed air cells, a plurality of insulating pad members secured to said backing sheet in spaced relation to each other, said pad members each comprising a loosely felted sheet of fibrous insulating material, said insulating pad members being substantially equal in width to the spaces between the supporting building elements to which the unit is to be applied, and spaced apart a distance equal to the width of said elements.

7. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting elements, a facing sheet and a backing sheet of fibrous material adhesively united to the opposite faces of said lath members to maintain the latter in spaced relation and form air cells therebetween, said facing sheet having a plurality of openings therein coinciding with the spaces between said lath members, for admitting plaster applied to said facing sheet into the interspaces between said laths to form interlocking keys and divide said interspaces into separate closed air cells, a plurality of insulating pad members carried on the back face of said panel in spaced relation, said pad members each comprising a loosely felted sheet of fibrous insulating material and a flexible paper wrapper completely surrounding said sheet and adhesively secured to both faces thereof, said wrapper over the area of one side of said sheet being in engagement with and adhesively secured to the rear face of said panel, said insulating pad members being substantially equal in width to the spaces between the supporting building elements to which the unit is to be applied, and spaced apart a distance equal to the width of said elements.

8. In a composite unit adapted for direct application to spaced supporting elements to form an insulated wall having a surface suitable for the reception of a plaster coat, a rigid panel member comprising a plurality of lath members disposed in spaced parallel relation and of a length to bridge a plurality of said spaced supporting members, a facing sheet and a backing sheet of fibrous material adhesively united to the 10 opposite faces of said lath members to maintain the latter in spaced relation and form air cells therebetween, means for sealing the ends of said air cells at the ends of said panel comprising a flexible strip extending over the edge thereof and 15 adhesively secured to the facing and backing sheets, and a plurality of individual insulating pad members adhesively secured to one face of said unit in spaced relation, said insulating pad members being substantially equal in width 20 to the space between the supporting elements to which the unit is to be applied and spaced apart a distance substantially equal to the width of said elements.

9. In a composite unit adapted for direct application to spaced supporting elements to form 25 an insulated wall having a surface suitable for the reception of a plaster coat, a rigid panel member comprising a plurality of lath members disposed in spaced parallel relation and of a length to bridge a plurality of said spaced supporting members, a facing sheet and a backing sheet of fibrous material adhesively united to the 30 opposite faces of said lath members to maintain the latter in spaced relation and form air cells therebetween said facing sheet having a plurality 35 of openings therein coinciding with the spaces between said lath members, for admitting plaster applied to said facing sheet into the interspaces between said laths to form interlocking keys and 40 divide said interspaces into separate closed air cells and means for sealing the ends of said air cells at the ends of said panel comprising a flex-

ible strip extending over the edge thereof and adhesively secured to the facing and backing sheets.

10. In a composite unit adapted for direct application to spaced supporting elements to form 5 an insulated wall having a surface suitable for the reception of a plaster coat, a rigid panel member comprising a plurality of lath members disposed in spaced parallel relation and of a length to bridge a plurality of said spaced supporting members, a facing sheet and a backing sheet of fibrous material adhered to the opposite faces of said lath members to maintain the latter in spaced relation and form air cells therebetween, one of said sheets having a coating of 10 waterproofing material covering one face thereof, said facing sheet having a plurality of openings therein coinciding with the spaces between said lath members, for admitting plaster applied to said facing sheet into the interspaces between 20 said lath members to form interlocking keys and divide said interspaces into separate closed air cells.

11. In a composite unit adapted for direct application to spaced supporting elements to form 25 an insulated wall having a surface suitable for the reception of a plaster coat, a rigid panel member comprising a plurality of composition strips disposed in spaced parallel relation and of a length to bridge a plurality of said spaced supporting elements, a facing sheet and a backing sheet of fibrous material adhered to the opposite faces of said composition strips to maintain the latter in spaced parallel relation and form air cells therebetween, said facing sheet 30 having a plurality of openings therein coinciding with the spaces between said composition strips for admitting plaster applied to said facing sheet into the interspaces between said strips to form interlocking keys and divide said interspaces into separate closed air cells.

CECIL R. PEMBERTON.
